UNITED STATES PATENT OFFICE.

JOSEPH DOYLE, OF WEST INDIANAPOLIS, INDIANA.

PIANOFORTE-ACTION.

No. 851,001.

Specification of Letters Patent.

Patented April 23, 1907.

Application filed January 11, 1906. Serial No. 295,609.

To all whom it may concern:

Be it known that I, JOSEPH DOYLE, a citizen of the United States, residing at West Indianapolis, in the county of Marion and State of Indiana, have invented certain new and useful Improvements in Pianoforte-Actions, of which the following is a specification.

This invention has relation to "pianoforte actions," so called.

It is the object of the invention to provide improvements in various parts of the action to the ends of securing an easier and generally "smoother" operation of the parts, and especially avoiding any tendency of the hammer to rebound, however rapid may be the strokes upon the key.

Other improvements incidental to the foregoing and to the perfect operation of the action are attained, as will appear from the description hereinafter given.

The drawings hereto annexed form a part of this specification and are to be referred to as such, of which drawings—

Figure 1 is a side elevation of the parts represented as in a state of rest. Fig. 2 is a similar view representing the parts as in action or after a key has been struck. Figs. 3 and 4 are detail views in perspective of several parts, showing their construction and mode of operation in detail. Fig. 5 is an enlarged sectional view of the damper-block, also disclosing in side view a portion of its actuating mechanism.

Like reference-numerals indicate like parts and features wherever they occur.

In the drawings, 1 designates the key, mounted on the balance-rail 2 in the manner shown in the drawings, which mounting, as stated hereinbefore, forms the subject-matter of a separate application for Letters Patent, or it may be mounted in any other suitable or well-known way. It is essential, however, that the mounting should be such that by a relatively quick and short depression of the key the hammer will be operated to strike the string with a quick stroke.

My improved action is operated by means of a jack 3 and rocker 4, fixed adjustably on the inner upper part of the key 1, similar to that used in square pianos.

5 designates the hammer, which when at rest leans against the felt-covered hammer rest-rail 6. The hammer-shank 5' connects the hammer-head with the hammer-butt 7, which is pivoted on a flange 8, secured on the

hammer-rail 9. At its pivoted point the hammer-butt is tenoned, and the tenoned point is set in a groove in the flange 8, as will be observed by an inspection of the drawings, 60 and the rail 9 is provided on its front face with a tongue or rib 9', which fits closely in a horizontal groove 8', made in the back of the flange 8, to hold the latter securely in position. The hammer-rail 9 is prepared at 65 its upper side to receive the damper-flange 10, recessed in its under side to fit on a tongue or rib 11 to keep it straight. The said damper-flange is further secured to the rail 9 by a screw 12, passing through the flange into 70 the rib 11. 13 designates the damper-lever, having a piece of felt 14 on its front edge, against which the upper end of a spring 15 bears, the said spring being secured at its lower end to the upper face of the flange 10. 75 The damper-lever is also provided on its lower front face with a piece of felt 16, which bears against a piece of felt 17', set in a recess 17, formed in the rear of the rail 9. A "spoon" 18, so called, bears against a piece 80 of felt on the front of the damper-lever near its lower end, said spoon being secured at its lower end to the back-check lever 19, as shown. The lower end of a wire 20 is inserted in the upper end of the damper-lever 85 13 and extends up straight to the damper-block 21, where it is bent forward at a right angle under said block, then straight up the front in a saw cut formed in the front face of the block to about its middle, where it is 90 turned back at a right angle and extends into a hole formed to receive it tightly, so as to insure it being kept in place and not becoming dislodged unintentionally. The block 21 is felted in the usual way to adapt it to bear 95 upon the string 22 and perform its common office.

23 is a straight bar of wood that rests at its lower end upon the key and extends vertically upward to the back-check lever 19, to 100 which it is pivoted. The bar 23 is felted at its foot where it bears on the key to prevent sound. A notch 24 is made in the side of the said bar just high enough to allow its upper felted edge to barely touch the link 25 when 105 the key is free, and the lower felted edge of the said notch is low enough to escape touching the said link 25 when the latter is in motion.

A spring 26 is connected with the jack 3 at 110 its heel and with the rocker, which spring tends to move the upper end of the jack

backward under the shoulder 27, formed on the lower end of the piece 28. A wire 29 extends up from the rocker behind the heel of the jack for the jack to lean against when the 5 action-frame is out. The jack is thus maintained in engagement with the shoulder 27 until a stroke or impulse is given to the key to operate the hammer, when the jack will be raised, raising the piece 28 and bringing the 10 projection 29^a on its lower end into contact with the regulating-button 30 on the lower end of the adjusting-screw 31, which screw extends through the regulating-rail 32, that extends from side to side of the piano-action 15 frame and is fastened at its ends by means (not shown) that may be quickly and easily operated to release the rail to remove it. The lower end of the regulating-buttons 30 are felted to obviate noise.

20 The beveled shoulder 27 has the vertical part lined or covered with felt, while the inclined part is covered with chamois-skin or soft leather to resist wear. In normal position the upper end of the jack will rest 25 against the felted vertical part of the offset and barely touch the leather-lined inclined part.

The piece 28 just above its lower end passes 30 through a mortise formed in the forward end of the link 25, and said piece 28 is pivoted in said mortise. The upper portion of the piece or bar 28 is made fast to a similar bar 33 by screws 34, and it may be grooved on the back to receive a registering tongue 35 formed on the face of the bar 33 to keep the two parts in alinement. The part of the bar 33 just below the hammer-butt is curved to the right or left, as shown at 33', and below said curve the bar 33 passes through a felted 40 notch in the back-check lever 19 and at its upper end extends into and is pivoted to the hammer-butt. The bars 33 and 28 in operation act as though they were composed of a single piece and serve to cause the hammer 45 to engage or strike the string when an impulse is given to the key and thereafter to draw the hammer away from the string as the upper end of the jack 3 engages the shoulder 27 of the bar 28, whereby the aforesaid 50 parts will be caused to assume the position indicated by Fig. 1. The splicing of the parts 33 and 28 is for the purpose of readily separating them, so that the hammer and other associated parts may be taken out 55 from the front without disturbing other parts.

The check-wire 34' is secured at its lower end in the forward end of the back-check lever 19 and extends upward and is provided 60 on its upper end with a pad 35, adapted to be brought into contact with a hammer-butt head 36, connected with the hammer-butt by a bar or wire 37.

The link 25 is pivoted at its front end on 65 the vertical bar 28 and at its rear end to a

flange-block 38, secured to the flange-rail 39 below a rib 40, above which rib a flange 41 is secured, to which the back-check link 19 is pivoted at its rear end. The notch 24 in the bar 23 is quite roomy so far as the operation 70 of the link 25 therein is concerned, the said link not being supposed to touch the bar 23 in its movements excepting the felt 42 on the upper side or wall; but to insure against rattling by the parts coming together the said 75 notch is lined with chamois-skin or the like.

An elbow-spring 43 is suitably secured in place at one end upon the flange-block 38. The wire of said elbow-spring is then passed downward under the lower end of the flange-block 38, and after making an angular turn therein it is extended forward to the bar 23, with its quick curve entering the notch 24 of the latter, so that the stress of the said elbow-spring is exerted upon the bar 23 to hold 80 the latter down in place and to return it after it has been raised by the key. Now when a key has been struck and held down the upper end of the jack will have left the shoulder 27 and stand entirely clear of the bar 28. Before 85 this action has taken place the bar 23 will have been raised, raising the link 19, and consequently tipping the spoon 18 against the damper-lever 13, throwing the damper back from the string. The check 35 meanwhile 90 will be brought against the back-stop 36, stopping the hammer a short distance from the string and holding it at this point. At this instant the bars 28 33 and their connections are hung, as it were, to the butt of the 95 hammer free from anything else to hold them up. The gravity of these last-mentioned parts is sufficient to hold the hammer against rebounding. When the key is released, the 100 gravity of the parts just mentioned, in conjunction with the springs, will quickly draw the hammer back, restore the damper to the wire, bringing the check to normal position and bringing the jack back from its place against the regulating-button with its upper 105 end into engagement with the shoulder 27 in the lower end of the bar 28. The bar 33 is curved to the right or left just below the hammer-butt to enable a workman or tuner of pianos to get behind the same with a 110 screw-driver or other means to adjust, remove, or replace parts, as may be necessary.

I claim—

1. The combination, with the hammer-butt, the jack and key, of a vertical bar pivoted at its upper end to the hammer-butt and operated from the jack, the pivoted check-lever, a second vertical bar pivoted at its upper end to said check-lever and resting at its lower end on the key, the check-wire 120 and its back-stop said check-wire being connected with the outer end of the check-lever, the damper and damper-lever, and a spoon connected with the check-lever and bearing at its free end against the lower end of the 125 130

damper-lever, the flange-rail, a flange thereon, a link pivoted at one end to the flange and at the other to the first-noted vertical bar pivoted to the hammer-butt.

- 5 2. The combination, with the hammer-butt, the jack and key, of a vertical bar pivoted at its upper end to the hammer-butt and operated from the jack, the check-lever, a second vertical bar pivoted at its upper end 10 to said check-lever, and resting at its lower end on the key and having a broad notch in its side, the check-wire and its back-stop said check-wire being connected with the outer end of said check-lever, and a spoon 15 connected with the check-lever and bearing at its free end against the lower end of the damper-lever, the flange-rail, a flange thereon, and a link pivoted at one end to the flange, extending through the broad notch 20 of said second vertical bar and pivoted to the first-noted vertical bar.
3. The combination, with a key and hammer-butt, of a vertical bar having a broad lateral notch and resting at its lower end 25 upon said key, a second vertical bar, means effecting connection between said hammer-

butt and said second vertical bar, a flange-rail, a flange thereon, a link pivoted to said flange and extending through said notch, and connected to said second bar and a spring 30 connected at one end to said flange, extending down behind the latter and under said link, its opposite or free end engaging the lower end wall of said notch.

4. The combination, with a key, of the 35 hammer and hammer-butt, the flange-rail, flanges upon said rail, the back-check lever pivoted upon one of said flanges, the link pivoted upon the other of said flanges, the connected-together bars one having its upper 40 end connected to the hammer-butt, and the other of said bars being connected to the latter link, a bar having its lower end resting upon the inner end of said key and its upper end pivoted to the back-check lever. 45

In testimony whereof I have signed my name to this specification in the presence of two subscribing witnesses.

JOSEPH DOYLE.
